UNITED STATES PATENT OFFICE.

CHARLES L. DICK AND MICHAEL WOEHL, OF CORYDON, INDIANA.

PLOW.

SPECIFICATION forming part of Letters Patent No. 236,146, dated January 4, 1881.

Application filed September 20, 1880. (No model.)

To all whom it may concern:

Be it known that we, CHARLES L. DICK and MICHAEL WOEHL, of Corydon, in the county of Harrison and State of Indiana, have invented certain new and useful Improvements in Plows; and we do hereby declare that the following is a full, clear, and exact description of the invention, which will enable others skilled in the art to which it appertains to make and use the same, reference being had to the accompanying drawings, which form a part of this specification.

Figure 1 is a side elevation of a sulky-plow embodying the improvements of our invention. Fig. 2 is a plan view. Fig. 3 is a rear elevation. Fig. 4 is a detail view of the adjustable wheel and its adjusting mechanism. Fig. 5 is an enlarged front elevation, partly in section.

This invention has relation to sulky-plows; and it consists in the improved features of construction and combination hereinafter fully described, and particularly pointed out in the claims.

Referring by letter to the accompanying drawings, A A' designate the supporting-wheels, one of which, A', is adjustable, as will be hereinafter explained.

B designates a vertical frame, the arm C of which is provided with a short axle, C', and the arm D is provided with a forwardly-projecting upwardly-curved arm, D', secured to or formed with a short horizontal extension, E. An upwardly-extending and forwardly-curved and perforated rack-arm, F, is also formed with or secured to the short extension E.

A short axle, G, with a short vertical arm, H, having flanges I at its lower end and flanges I' at its upper end, is provided with a forwardly-extending arm, J, and a vertical rearwardly-inclined latching-lever, K. The arms D' and J are connected at their forward ends by a hinge or pivot joint, L. The flanges I I' embrace the curved perforated rack-arm F, and the detent M of the latching-lever K enters the perforations in the rack-arm F and holds the adjustable wheel A' in the position to which it may have been adjusted by the movement of the latching-lever K. The adjustable wheel A' rides in the furrow, and the object for which it is intended is to keep the frame in a horizontal plane during the operation of plowing.

Within the arms C D of the vertical frame B is a vertically-sliding frame, N, the flanges N' N'' of which serve as ways to hold it in place in said frame B. This sliding frame N is provided at the lower ends of its arms with boxes or bearings O, in which the shaft P is supported. This shaft P has a flat central portion, over which a loop, P', rises, and between the loop and the flat portion of the shaft the plow-beam Q of any kind of a beam-plow may be secured by wedges or in any other suitable manner.

About midway of the cross-bar Q' of the vertical frame B, and to the under side of the same, is pivoted an upwardly-curved notched arm, R, in such a manner that it may be swung on its pivot in a horizontal plane.

To the right-hand side of the frame B, and above the arm D of the same, is pivoted or hinged, at R', a horizontally-curved notched arm, R'', having its motion on its pivot in a vertical plane.

Upon the top of the cross-bar Q', and upon the pivot of the vertical arm R, is a stirrup, R³, in which is fulcrumed a latching-lever, S. The latch S' of this lever S is a double latch, and consists of a sleeve surrounding the lever S, the top portion, S², projecting forward of the side portions, S³. The top portion engages the notches of the vertical arm R, and the left-hand side portion, S³, engages the notches of the horizontal arm R'', so that the latch S' holds the lever S both to its vertical and its horizontal adjustments. The forward end of the latching-lever S is bifurcated, and in this bifurcation T is pivoted the upper end of a forked frame, T'. Between the arms T² of the frame T', and at the lower end of the same, is pivoted a loop or frame, U, for the reception of the plow-beam in front of the point of its connection with the journaled shaft P. The forked frame T' straddles the tongue V, which extends forward from the cross-bar of the sliding frame N, and is strengthened by braces V', extending upward and forward from the lower ends of the arms of the sliding frame N.

A chain, W, extends from the latching-lever S to the tongue, to limit the distance to which the plow may be depressed.

A seat, X, is supported by braces X' X² X³, extending rearward from the vertical frame B.

Y designates the plow.

As has been before stated, the adjustable wheel A', through its latching-lever K, perforated arm F, arms D' and J, and detent M, permits the plow and frame to be maintained 5 in a horizontal plane.

The pivoted latching-lever S, having both a vertical and a horizontal swing through the pivoted ratchet-arms R R², elevates the plow-beam by means of the sliding frame N, and 10 also shifts it from left to right, or vice versa, through the pivoted forked frame T'.

The advantages of this construction are obvious. Two levers only are used to effect all 15 the adjustments necessary, and they are both in convenient reach of the driver. The advantage of being able to shift the plow at the same time that it is raised is a valuable one. It is of great use in plowing around stumps and stones and in turning corners.

20 Any style of beam-plow may be connected with this sulky. The sulky is simple and inexpensive, and is not liable to easily get out of order.

Having thus fully described our invention, 25 what we claim as new and useful, and desire to secure by Letters Patent of the United States, is—

1. In a sulky-plow, the combination, with the

vertical frame B C D, provided with the short axle C', of the forwardly-projecting upwardly-curved arm D', having a short horizontal extension, E, provided with an upwardly-extended and forwardly-curved and perforated rack-arm, F, short axle G, having short vertical arm H, provided with flanges I I' at its lower and upper ends, forwardly-extended pivoted arm J, latching-lever K, and detent M, the several parts constructed and relatively arranged to operate substantially in the manner herein shown and described. 30

2. In a sulky-plow, the vertical sliding frame N, having the bearings O, the shaft P, carrying loop P', and the pivoted forked arm T', carrying the loop U, in combination with the pivoted latching-lever S, vertical arm R, horizontal arm R², stirrup R³, and tongue V, constructed and operating substantially as and 35 for the purposes set forth. 40

In testimony that we claim the foregoing as our own we have hereto affixed our signatures 45 in presence of two witnesses. 50

CHARLES L. DICK.
MICHAEL WOEHL.
